(57) **CLAIM**

I claim the ornamental design for a computer mouse housing, as shown and described.

DESCRIPTION

FIG. 1 is a top, front perspective view of a computer mouse housing of the present invention, showing the doors in a closed position;

FIG. 2 is a top, rear perspective view thereof;

FIG. 3 is a front elevation view thereof;

FIG. 4 is a rear elevation view thereof;

FIG. 5 is a top plan view thereof; and,

FIG. 6 is a right side elevation view, the left side view being a mirror image thereof.
